Primary Examiner — George D Kirschbaum*Assistant Examiner* — Celse Moore, Jr.(74) *Attorney, Agent, or Firm* — Lerner, David, Littenberg, Krumholz & Mentlik, LLP(57) **CLAIM**

The ornamental design for an autonomous vehicle exterior, as shown and described.

DESCRIPTION

FIG. 1 is a front perspective view of an autonomous vehicle exterior according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of the autonomous vehicle exterior of FIG. 1 in a configuration showing a door in an open position; and,

FIG. 9 is a top plan view of the autonomous vehicle exterior of FIG. 13 in a configuration showing a door in an open position.

The broken lines shown illustrate portions of the autonomous vehicle exterior that form no part of the claimed design.

1 Claim, 9 Drawing Sheets(56)
